UNITED STATES PATENT OFFICE.

ROBERT LEE CALLAHAN, OF LOUISVILLE, KENTUCKY.

TRANSPORTATION MACHINERY.

Application filed April 4, 1925. Serial No. 20,766.

The present invention relates to improvements in transportation machinery, and more particularly refers to an improved conveyor for use particularly in connection with the loading and unloading of railway box cars.

To this end, an object of the invention is to provide an apparatus embodying a conveyor for the purpose of moving goods in or out of the car from the center side door to either end thereof; and at the same time to provide drive means for the conveyor adapted to shift the conveyor back and forth, whereby the conveyor may retreat as the goods are stacked in the ends of the cars or may be moved forward from the center toward the car ends, as the merchandise is removed therefrom.

The invention has for its further object to provide a conveyor and co-ordinate drive mechanism, which will not only operate the conveyor for the purpose of transferring the goods from one end of said conveyor to the other, but will also act to shift the conveyor bodily in and out of the car and cause it to advance or retire accordingly as goods are being withdrawn or loaded into said car.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a side elevation of an improved transportation machine constructed according to the present invention;

Figure 2 is an enlarged plan view of the drive mechanism;

Figure 3 is a fragmentary vertical section taken through the device with parts broken away;

Figure 4 is a side elevation of the drive mechanism;

Figure 5 is a transverse section on a magnified scale taken through the device on the line 5-5 in Fig. 1;

Figure 6 is a cross-section of the frame-work taken on the line 6-6, also in Fig. 1;

Figure 7 is a cross-section taken on the line 7-7 in Fig. 10;

Figure 8 is a cross-section taken through the pulley at an angle of 45° to that of Fig. 7;

Figure 9 is a diagrammatic view showing the machine applied to use in a box car;

Figure 10 is a side elevation of the end portion of the conveying machinery frame;

Figure 11 is a top plan view on an enlarged scale of the conveyor;

Figure 12 is a plan view on a much magnified scale of the conveyor cleat; and

Figure 13 is a section taken on the line 13-13 in Fig. 12.

Referring more particularly to the drawings, the device embodies an endless conveyor and a frame for supporting the same, comprising the side rails 14 and 15, which extend in parallel and appropriately spaced relation, and are also preferably curved, as indicated in Figs. 9 and 11, for the purpose of enabling the conveyor to pass through the side center opening 16 of the freight or railway box car, indicated at 17 in Fig. 9.

The side rails 14 and 15 may be connected together at appropriate points by the cross-bars 18 shown in Fig. 6, and the opposite ends of said rails 14 and 15 are connected by the end guard or handle rails 19 and 20. The side rails 14 and 15 are supported upon the legs 21 and 22 mounted in pairs near the end portions of the rails and being preferably connected by the transverse braces 23 shown in Fig. 6. The legs are also preferably reinforced by the diagonal braces 24, shown in Fig. 1, as connected between the lower portions of the legs and end portions of the rails 14 and 15. The legs 21 and 22 are preferably of tubular metal to admit of the telescoping therein of the shanks 25 carrying the rollers or casters 26, upon which the conveyor as a whole may roll into and out of the box car or other place where the loading or unloading is to be effected. Set screws 27 are threaded into the tubular legs in order to take against the shanks 25 of the casters and hold same at the adjusted elevation.

As shown in Figs. 1 and 5 particularly, the side rails 14 and 15 serve to support at suitable intervals the posts or standards 28 and 29, being tied together centrally by the lateral braces or connecting bars 30 and having pairs of inwardly extending arms 31 and 32 at their upper ends for carrying the companion spaced and parallel channel bars 33 and 34; and said posts 28 and 29 further having near their lower portions similar inwardly extending arms 35 and 36 for supporting the lower pair of channel beams 37 and 38. The channels of the beams extend outwardly and the upper pair of

channel beams is spaced equi-distantly above the center transverse braces 30, as compared with the distance the lower set of channel beams 37 and 38 are set below said brace 30. The channel beams are arranged with their channel portions outwardly and a space is left between the channel beams for the passage respectively of the upper and lower run of the endless conveyor. The upper and lower pair of channels are connected at their end portions, as indicated in Figs. 1 and 10 by the curved or rounded channel sections 39, thus forming continuous or endless tracks for the movement of the rollers of the conveyor, as hereinafter explained.

Now, the conveyor itself consists of the endless cable 40 carried by the end pulleys 41 and 42 having the grooved peripheries 20 43 as shown in Fig. 7 and being mounted upon the transverse shafts 44. The shaft 44, as shown in Figs. 7 and 10, is journaled in the plates 45 and 46 supported by the metallic or other straps 47 and 48, which 25 have their upper and lower ends respectively bent into the channel portions of said upper and lower pairs of channel beams, to which they are secured as by the rivets 49. Shoulders 50 are provided by the bending 30 of the parts as just stated, and such shoulder will form in addition to the rivet a supporting means for the shaft and other parts, and will take the strain off the rivets.

The pulleys 41, as shown in Figs. 1 and 35 8, are preferably in the form of a cross, as viewed from side elevation. In other words, the pulleys are not continuous as to their peripheries, but are provided with the cut-out portions 51.

40 As shown in Figs. 7 and 10, one projecting end of the shaft 44 is provided with a flat bottomed notch 52 to receive the straight edge of the latch 53 pivoted at 45 54 to one supporting plate 45. When the latch is in the lowered position shown in Fig. 10, obviously the shaft 52 will be prevented from rotating, and the conveyor can not be driven, as the pulleys 41 and 42 are fixed tightly to their shafts 44. In 50 this condition, the drive mechanism for the conveyor is adapted to move the entire conveyor and its support inwardly or outwardly of the car, as explained later.

55 The cable 40 of the conveyor contains at spaced equi-distant intervals spools 55 secured tightly thereon and having the enlarged ends 56 and 57 with the outer rounded surfaces 58 and 59. The intermediate body portions of the spools are 60 adapted to receive the transverse straps 60 and 61 secured above and below the spool and being provided with pairs of side rollers 62 and 63 to roll on vertical axes and 65 against the inner faces of the channel beams 33, 34, 37 and 38. The outer ends of the

transverse straps 60 and 61 are formed into the substantially U-shaped stirrups 64 and 65 to accommodate the rollers 66 and 67 journaled on substantially horizontal axes and disposed in rolling contact with the outer and inner flanges of the channel beams. The rollers 66 and 67 serve to support the load and maintain the conveyor cable against rising or falling, while the other rollers 62 and 63 prevent the conveyor cable 75 from vibrating laterally or getting out of a proper central position between the beams.

The straps 64, besides supporting the rollers, also on account of their height above the cable and spool serve as excellent supports for the cleats 68, which may be made in the form shown in Fig. 11, or other form as desired. These cleats or the reduced ends thereof are riveted or otherwise secured to the straps. The cleats may be depressed centrally, as shown in Fig. 5, to better support and hold the load indicated in dotted lines at 69 in Fig. 5. The goods are represented as in the form of sacks, although the conveyor is adapted to the transportation of any merchandise. Rails 70 and 71 having tapering inner edges 72 are supported above the posts or standards 28 and 29 and run longitudinally of the conveyor for the purpose of supporting the outer portion of the sack 69.

The conveyor is driven by the mechanism mounted upon the platform 73 disposed for movement on the rollers or casters 74. The platform is provided with spaced frames 75 and 76, shown in Figs. 1 and 5, having the vertically adjustable bearings 77 and 78 for the shaft 79; appropriate adjusting screws 80 and 81 being arranged to engage the upper and lower portions of the blocks to lift and lower the same. The shaft 79 extends at one side beyond the bearing block 77, where it carries fixedly the sprocket 82 driven by a chain 83, shown more particularly in Fig. 4. This chain also engages at 105 its other end the sprocket 84 on the counter shaft 85. This counter shaft is journaled in appropriate bearings 86, shown more particularly in Fig. 2, and carries the gear wheel 87, disposed in mesh with the pinion 110 88 of the electric or other motor 89.

The frames 75 and 76 serve to support the diagonally extending angle bars 90 and 91, shown to best advantage in Fig. 3, said bars being connected at their lower convergent ends to the rod 92 extending across between said frames 75 and 76. At their upper divergent ends said diagonal bars or arms carry the shafts 93 and 94, on which are carried pairs of grooved wheels 95 and 96 125 spaced apart the same distance as the spacing of the rails 14 and 15 of the conveyor support, whereby said grooved wheels 95 and 96 may engage the under sides of said rails to guide the movement of the carriage 130.

73 back and forth beneath the conveyor, and conversely to guide the conveyor rail supports back and forth on the drive mechanism.

5 On the shaft 79, which is driven as aforesaid from the electric or other motor 89, is disposed a driving wheel for coming in contact with the spools of the conveyor for the purpose of driving said conveyor. This 10 drive wheel is composed of a pair of spiders 97 and 98, shown in Figs. 2, 3 and 5 particularly, held spaced apart by the spacing sleeve 99 on the shaft between said spiders. These spiders have preferably four radiating arms, as indicated in Fig. 3, and upon the outer ends of these arms are rotatably supported pairs of rotary discs or wheels 100 and 101, spaced apart to straddle the conveyor cable 40 and having suitably beveled inner edges 102 to conform substantially to the oppositely and reversely curved portions 58 and 59 of the spool heads against which these discs are arranged to engage in the act of driving the spools and incidentally the conveyor cable. The angular distance between the spider arms will correspond substantially to the linear distance between adjacent spools on the conveyor cable, whereby on the rotation of the shafts 79 and drive wheel the pairs of rotary discs 100 and 101 will be brought successively into the subsequently presented spaces between spools, whereby said discs may engage behind the spool heads, for the purpose of urging the spools forwardly.

40 The electric motor may be of the reversible type or provision may be made for effecting the rotation of the drive wheel in either direction, so that the conveyor may be driven forwardly or reversed, as desired.

45 In the use of the device, the drive wheel is rotated as explained, the discs 100 and 101 coming in contact with the spools and advancing same. The sacks of material indicated at 69 in Fig. 5 are placed upon the conveyor at one end, for instance the end outside of the car, shown in Fig. 9, and when these sacks arrive at the inner end of the conveyor, they are automatically dumped or 50 may be lifted by hand and stacked in the car end. As the car becomes loaded, it is necessary to withdraw the conveyor gradually to admit of the piling of the goods in the car. This movement of the conveyor is 55 also accomplished by the drive mechanism. The latch 53 in Fig. 10 is moved to the position shown in Fig. 10 to engage the notch in the shaft 44, thus preventing the rotation of the shaft or the movement of the conveyor about its pulleys 41 and 42. The 60 wheels 74 of the carriage 73 are blocked, and on rotation of the drive wheel, the entire conveyor mechanism will be shifted back and forth in accordance with the direction 65 of rotation of the drive wheel, the entire

mechanism sliding on the casters 26 and being guided in its movement by the grooved wheels 95 and 96 of the drive mechanism, which engage the side rails 14 and 15.

70 When the conveyor is shifted to the new position, the latch 53 is raised and the wheels 26 may be blocked, thus permitting the drive wheel to resume the driving of the endless conveyor. The conveyor is movable upon the arc of movement indicated by the full and dotted lines in Fig. 9, so that in the loading of goods into the car, the conveyor may be gradually withdrawn outwardly through the door 16. In case goods are to be unloaded from the car at its destination, the conveyor is shifted inwardly from time to time, as the goods are removed in front of it. The conveyor may be placed alternately in both ends of the car, and either end of the conveyor may be first inserted.

75 The conveyor shown is arranged on the arc of a circle, as it will be most convenient to embody the device in this form for use in connection with box car loading and unloading, but it will be understood that the device may be made in other forms to adapt its use in other connections.

80 It is obvious that various changes and modifications may be made in the details of construction and design of the above specifically described embodiment of this invention, without departing from the spirit thereof, such changes and modifications being restricted only by the scope of the following claims:

85 What is claimed is:

1. A transportation machine comprising a shiftable ground support, conveying means moving with respect to said support and movable bodily with the support, and coordinate drive means for both driving said conveyor with respect to the support when said support is stationary and for shifting the conveyor and support bodily.

90 105 110 115 120 125 130

2. Transportation machine comprising shiftable drive means, an elongated curved ground support shiftable with respect to said drive means, and a conveyor arranged to be driven by said drive means and also to be shifted bodily by said drive means together with said support.

135 140 145 150 155 160 165 170

3. Transportation machinery comprising an endless conveyor, a wheeled support for the conveyor, means whereby the conveyor may be secured against movement on said wheeled support, and drive means for engaging with said conveyor to drive the same while the support is held against movement and also acting to shift the conveyor and the wheeled support bodily when said means is engaged.

175 180 185 190 195 200

4. Transportation machinery comprising an elongated wheeled support, an endless conveyor mounted on said support to move therewith, means to fix the conveyor against

movement with reference to the support, a driving carriage movably mounted beneath the conveyor and having guide means movable along said support, said drive means having a drive wheel for engaging with said conveyor.

5. Transportation machinery comprising an endless conveyor, an elongated wheeled supporting means therefor, means to secure 10 the conveyor against endless travel, a wheeled carriage beneath said conveyor having guide rollers for engaging with said support, and a drive wheel on said wheeled carriage for directly engaging the conveyor.

15 6. Transportation machinery comprising a conveyor including an endless cable, spools thereon having rounded heads, pairs of pivoted discs adapted to enter the spaces between adjacent spools and to engage the 20 rounded ends of said spools at opposite sides of the cable, said discs having beveled edges to conform to the rounded heads of the spools, and means to revolve said discs.

25 7. Transportation machinery comprising a conveyor including an endless cable, spools thereon, straps secured to said spools, rollers carried by said straps, beams at the sides of the cable engaged by said rollers, other rollers of said straps engaging the 30 edges of said beams, cleats secured to said straps, and means for engaging the ends of the spools to drive the conveyor.

35 8. Transportation machinery comprising a frame member and upper and lower pairs of beams carried by said frame, an endless cable movable between said beams, means for guiding the movement of the cable be-

tween said beams, cleats movable with said cable for supporting the goods at the center parts thereof, rails carried by said frame 40 substantially parallel with said cable and spaced from said beams for receiving the outer portions of said goods, and means for driving the conveyor.

9. A transportation machine comprising 45 an elongated ground support movable back and forth over the ground, an endless conveyor carried with said ground support, means for locking said conveyor against movement, and a carriage separate and distinct from said ground support movably mounted beneath said ground support and adapted to be held stationary thereunder, and a power wheel on said carriage adapted 50 to strike parts of the conveyor for moving the same or, when said conveyor is locked against movement, for shifting the combined conveyor and ground support over the ground.

10. A transportation machine comprising 55 an elongated wheeled ground support shift- 60 able freely back and forth over the ground, an endless conveyor carried by said support, means for locking the conveyor against movement, a power carriage independent of 65 said ground support and placed beneath the same, guide means on said carriage cooperating with said support, and a power wheel on said carriage meshing with said conveyor for driving the same and, when 70 said conveyor is locked against movement, for shifting the entire ground support and conveyor along the ground.

ROBERT LEE CALLAHAN.
